W. W. LYNES,
POTATO DIGGING MACHINE,
APPLICATION FILED JUNE 11, 1918.

1,301,857.

Patented Apr. 29, 1919.

INVENTOR

William Wellington Lynes

By *Robert Livingston*
Atty.

UNITED STATES PATENT OFFICE.

WILLIAM WELLINGTON LYNES, OF KAMLOOPS, BRITISH COLUMBIA, CANADA.

POTATO-DIGGING MACHINE.

1,301,857.

Specification of Letters Patent. Patented Apr. 29, 1919.

Application filed June 11, 1918. Serial No. 239,426.

To all whom it may concern:

Be it known that I, WILLIAM WELLINGTON LYNES, a subject of the King of Great Britain, and a resident of the town of Kamloops, in the Province of British Columbia, Canada, have invented certain new and useful Improvements in Potato-Digging Machines, of which the following is a specification.

10 My invention relates to improvements in potato digging machines, and the object of my invention is to provide a machine of simple construction by means of which potatoes may be dug up out of the soil mechanically and in a highly efficient manner.

I attain this object by the construction illustrated in the accompanying drawings in which—

20 Figure 1 is a side elevation of my machine.

Fig. 2 is a front end view with the front guide and the front of the frame removed.

Fig. 3 is a front end view showing the cylinder guide arrangement.

25 Fig. 4 is a plan view of the cylinder.

Fig. 5 is a view, in part section, of the front end cylinder guide.

Similar figures of reference indicate similar parts throughout the several views.

30 1 indicates the frame of the machine, which frame serves to carry the driver's seat 2, and the operating mechanism, and to the front end of which a team may be attached for pulling the machine when

35 using it. The frame toward its rear end is supported on wheels 3 and 4, these wheels being rotatable on an axle 5 fixed to the frame, while the front end of the frame is provided with wheels 6 rotatably mounted

40 on arms 7 pivoted to the frame at 8 and swingable to or from the vertical position to raise or lower the front end of the frame by arm 9 and link 10 operated by a hand lever 11.

45 For a portion of its length toward its rear end the frame 1 is formed of two parallel members 12 and 13 and to these are secured, adjacent their front and rear ends respectively rings 14 and 15, within which

50 rings is concentrically mounted a cylindrical open-ended basket 16 provided with encircling bands 17 and 18 formed preferably of channel section so that guide channels or grooves 19 are provided in which

grooves operate as the basket revolves guide 55 rollers 20 secured to the inner periphery of the respective rings 14 and 15.

The basket 16 is formed preferably of wires spaced apart, as indicated in Figs. 1 and 4, each wire extending spirally from 60 one end of the basket to the other, and encircling the basket and secured to it at a suitable point is an annular toothed rack 21, adapted to be operatively engaged by a spur gear 22 secured to a transverse shaft 65 23 rotatably mounted in bearings 24 and 25 hingedly connected to the frame, as indicated at 26 in Fig. 1, so that they may be raised or lowered to carry the gear 22 out of or into engagement with the rack 21 by 70 means of co-operating levers 27 and 28 actuated when required by a hand lever 29. The teeth of the rack 21 and gear 22 are cut to the required inclination, as indicated in Figs. 1 and 5, and the shaft 23 to which the 75 gear 22 is secured is provided at each end with gears 30 and 31 meshing respectively with large gears 32 and 33 secured to the inside of the frame wheels 3 and 4.

34 indicates the digging element, which is 80 formed of strong material after the manner of a spade blade and is secured rigidly to the frame between and adjacent the front ends of the parallel members 12 and 13, its length being such that its lower end extends the necessary distance into the ground when the machine is in operation while its upper end extends into the mouth of the basket so that the potatoes will fall thereinto, its sides being turned upwardly at 90 right angles, as indicated at 35 and 36 in Fig. 2.

37, 38, 39 and 40 indicate wires supported within the basket at each quarter of its circumference and spaced apart from the outer 95 wires, each of these wires being also carried spirally from and parallel to its contiguous outer wire, being provided for the purpose of assisting the travel of the potatoes through the basket from end to end 100 during the operation of the machine, although these wires are not absolutely necessary.

The manner in which the machine operates will be apparent on reference being had 105 to the drawings, particularly to Fig. 1, as it will be seen that, on moving it ahead by means of a team of horses or other motive

power, the element 34 will dig the potatoes up and they will travel up the inclined blade, falling over the upper end of the same into the rotating basket, from end to end of which they will be caused to travel by the spiral configuration of its cylindrical wall, the basket being rotated by the mechanism already noticed and which mechanism is actuated by the large gears 32 and 33 on the frame wheels. On reaching the opposite end of the basket the potatoes may be collected in a sack attached thereto and into which they fall, or they may be collected by any other suitable method.

15 It will be seen, therefore, that I have devised a potato digging machine which is simple in construction and action and capable of highly efficient work. As many changes could be made, however, in the construction described in the foregoing, within the scope of the claim, it is intended that all matter contained in the accompanying specification and drawings shall be inter-

20

preted as illustrative and not in a limiting sense.

25

What I claim as my invention is:

In combination a frame comprising side bars, rings supported thereon at front and rear, a cylindrical basket of spirally arranged wire revolvably mounted in said rings, a toothed rack surrounding the basket, a shaft extending transversely of the basket above the same, carrying wheels, gearing between said transverse shaft and the carrying wheels, a gear on the transverse shaft meshing with the rack on the basket, pivotally mounted supporting means for the transverse shaft whereby the said shaft with its gear may be lifted, connections manually operable for moving said support, and digging means at the forward end of the basket, substantially as described.

Dated at Kamloops, B. C., this 9th day of May, 1918.

WILLIAM WELLINGTON LYNES.
